UNITED STATES PATENT OFFICE.

FERDINAND HORMANN, OF PHILADELPHIA, PENNSYLVANIA, ASSIGNOR TO
HIMSELF AND FREDERICK ROHRBACHER, OF SAME PLACE.

DESIGN FOR A GLOBE FOR ELECTRIC OR OTHER LIGHTS.

SPECIFICATION forming part of Design No. 21,391, dated March 8, 1892.

Application filed February 2, 1892. Serial No. 420,120. Term of patent 7 years.

To all whom it may concern:

Be it known that I, FERDINAND HORMANN, a citizen of the United States, and a resident of Philadelphia, Pennsylvania, have invented 5 a Design for a Globe for Gas, Electric, or other Lights, of which the following is a specification.

My design for the globe is fully shown in the accompanying drawings, in which—

10 Figure 1 is a side view of a globe embodying the design. Fig 2 is a transverse section on the line 1 2, Fig. 1; and Fig 3 is a transverse section on the line 3 4, Fig. 1.

The globe has the usual bowl shape in general outline; but extending around the globe, about the center of the same, is a raised band or ring *a*, (best shown in the sectional view, Fig. 2,) and extending from the top of this band to the top of the globe is a series of 15 tapering protuberances *b*, similar tapering

25 protuberances *d*, extending from the bottom of the central ring or band *a* to the lower rim or collar *f* of the globe. The ring and the tapering protuberances may be ornamented as desired without departing from the essential characteristics of my design, these characteristics being the raised central band *a* and the tapering protuberances *b* and *d*, extending upward and downward therefrom.

I claim—

30 The design for a globe for gas, electric, or other lights, substantially as described, and as shown in the accompanying drawings.

In testimony whereof I have signed my name to this specification in the presence of 35 two subscribing witnesses.

FERDINAND HORMANN.
